COTTON CLEANING MACHINE

Henry T. Ahrens, Charlotte, Tex.

Application May 27, 1938, Serial No. 210,502

1 Claim. (Cl. 19—93)

This invention relates to cotton cleaning machines and an object of the invention is to provide a machine which will insure a thorough cleaning of the cotton, and the invention embodies an air-tight container, one side of which consists of a plurality of apertured concaves with which cooperate rotary beaters in a manner assuring a thorough agitating of the cotton, loosening the dirt and dust therefrom, while at the same time causing the cotton to continue its passage through the casing, the concaves being perforated to permit the dirt and dust separated from the cotton to pass therethrough.

The invention together with its objects and advantages will be best understood from a study of the following description taken in connection with the accompanying drawings wherein:

Figure 1 is a bottom plan view of the cleaner.

Figure 2 is a horizontal sectional view through the cleaner,

Figure 3 is a vertical longitudinal sectional view through the cleaner, and

Figure 4 is a vertical transverse sectional view through the cleaner.

Referring to the drawings by reference numerals it will be seen that in accordance with the present invention the cleaner comprises a suitable supporting frame that embodies a pair of opposed parallel bars 5—5 respectively supported by legs 6.

The bars 5 support therebetween a relatively shallow broad casing 7 that at one end is provided with an inlet funnel 8 and at its opposite end provided with an outlet 9.

The walls of the casing 7 are substantially imperforate except for the bottom wall thereof, and which latter wall consists of a plurality of integral concaves 10, arranged in a longitudinal series extending substantially from one end to the other of the casing.

The concaves 10 are perforated as at 11.

Arranged within the casing 7 is a plurality of transversely disposed shafts including a plurality of shafts 12 and a shaft 13', there being one shaft opposite each concave.

Carried by each of the shafts 12 is a longitudinal series of beater arms or paddles 13, and the paddles 13 are arranged in pairs, each pair of paddles having the shank portions thereof integral with a hub 14 suitably secured to the shaft. Also, and as shown, alternate pairs of paddles 13 are arranged substantially at right angles to the intermediate pairs of paddles.

Also, and as shown, each paddle has the shank thereof at its free end merging into a substan-

tially V-shaped head that at its outer edge is thickened and provided with a groove 15 in which is secured through the medium of rivets or other fastening elements 16 one edge of a blade 17 which is formed of rubber or similar material.

The blades 17, as the paddles revolve, have wiping engagement with the concaves as shown and thereby serve to sweep the concaves in a manner agitating the cotton loosening the dirt and dust therefrom, so that the dirt and dust 10 passes from the casing through the perforations 11 in the concaves.

Also the arrangement of the paddles is such, and as shown, that each concave for the full length thereof is swept completely by the paddles.

As is also apparent the revolving paddles serve to force the cotton longitudinally through the casing from one concave to the other.

The shaft 13' which is disposed adjacent the outlet end 9 of the casing has mounted thereon a paddle wheel which consists of an elongated hub 18 that is substantially of a length equal to the length of the shaft 13', and radiating from the hub 18 are blades 19 that are of a length corresponding to the length of the hub 18.

The blades 19 are preferably formed of rubber and extend from one side to the other of the casing 7. The blades 19 have wiping engagement with the associated end concave 10 and also have wiping engagement with a curved top wall surface 7a provided above the outlet 9 so that the blades 19 cooperate with the wall surface 7a for providing, as it were, a revoluble closure for the outlet 9 with the result that at the outlet end 9 thereof the casing is rendered substantially airtight. It will thus be appreciated that with the air being thus prevented from escaping through the outlet 9 the pressure of air above the concaves 10 will be sufficient to force all dust and dirt through the perforations 11 in the concaves thus insuring further a thorough cleaning of 40 the cotton as it passes from the inlet to the outlet end of the casing.

Also the blades 19 act on the cotton to force the same outwardly of the casing 7 through the opening 9.

In actual practice it will be understood that the cotton is forced into the casing 7 at the funnel-equipped end 8 thereof through the medium of a blower, and through the medium of the air pressure and the revolving action of the beaters forced longitudinally through the casing 7 passing from one concave to the other and finally discharged, free of dust and dirt, from the casing 7 at the opening 9 onto a suitable con-

veyor provided to receive the cotton (the conveyor not being shown). The conveyor would be used for conveying the cotton to, for example, the burr cleaning machine prior to the passage 5 of the cotton to the gin stand.

It will also be apparent that instead of attaching a blower to the inlet 8 for forcing air under pressure through the casing a suction device may be suitably associated with the cleaner 10 beneath the concaves 10 for sucking the cotton into the casing 7 and the dust and dirt through the perforations 11 in the concaves 10, the revolving paddles or blades pushing the cotton lengthwise of the casing 7 from the inlet to the outlet end thereof.

An advantage of this device is in the provision of the imperforate blades 19 on the paddle wheel at the outlet end of the casing which blades, as previously stated, serve to prevent 20 escape of air pressure from the casing except through the perforations 11 in the concaves.

It is thought that a clear understanding of the construction, utility and advantages of an invention of this character will be had without 25 a more detailed description.

Having thus described the invention what is claimed as new is:

In a cotton cleaning machine an elongated

casing adapted to have cotton to be cleaned to be passed therethrough, said casing being provided at one end with an inlet and at the opposite end with an outlet, and said casing also having a bottom wall composed of a series of integral 10 perforated concaves, and beaters rotatably mounted in the casing opposite each concave, each of all of said beaters except one of said beaters comprising a shaft having a plurality of paddles arranged thereon, said paddles being arranged in pairs with the paddles of alternate pairs disposed at right angles to the paddles of intermediate pairs, and the said one of said beaters embodying an elongated hub having blades radiating therefrom, said blades being of a 15 length slightly less than the width of said casing and being formed of rubber, and each of the paddles of the first-named beaters embodying a shank having an enlarged head at the free end thereof and a wiping blade secured to said head, 20 said head being provided with a groove accommodating one edge of the wiping blade, and said wiping blade being formed of rubber and having wiping engagement with a concave to sweep the dirt and dust through the perforations in the 25 concave.
